DECANTER

Ernest L. Du Pree, Weston, Conn., assignor to Schenley
Industries, Inc., New York, N. Y., a corporation of Delaware

Application October 31, 1956, Serial No. 43,613

Term of patent 14 years

(Cl. D58—8)

The drawing has been shaded to illustrate contrasting appearance.

I claim:

The ornamental design for a decanter, as shown and described.
